UNITED STATES PATENT OFFICE.

BEN F. CULVER AND WILLIAM H. DOYLE, OF PLATTEVILLE, WISCONSIN; SAID CULVER
ASSIGNOR TO SAID DOYLE.

BARREL-HOLDING DEVICE.

Application filed May 18, 1922. Serial No. 561,912.

To all whom it may concern:

Be it known that BEN F. CULVER and WILLIAM H. DOYLE, citizens of the United States, residing at Platteville, in the county 5 of Grant and State of Wisconsin, have invented certain new and useful Improvements in Barrel-Holding Devices, of which the following is a specification.

The present invention relates to a supporting device for barrels.

An important object of the invention is to provide a device of the above mentioned character, which may be applied to a barrel in a convenient manner, and will support 15 the barrel so that it may be easily shifted to selected positions.

An important object of the invention is to provide a device of the above mentioned character, all parts of which are adapted to 20 be folded so that the device is flat and will occupy the least space when not in use.

Other objects and advantages of the invention will be apparent during the course of the following description.

25 In the accompanying drawings forming a part of this specification and in which like numerals are employed to designate like parts throughout the same,

Fig. 1 is a perspective view of the supporting device, showing a barrel held therein,

Fig. 2 is a similar view with the barrel removed,

Fig. 3 is a perspective view with the barrel receiving element horizontally arranged,

Fig. 4 is a perspective view of the device, showing the parts collapsed, and,

Fig. 5 is a side elevation of the same.

In the drawings, wherein for the purpose 40 of illustration is shown a preferred embodiment of our invention, the numeral 10 designates a pair of legs, suitably connected at their lower ends by bars 11, which are preferably crossed, as shown. The numeral 12 designates a coacting pair of legs, disposed 45 opposite the first pair of legs. The legs 12 are preferably connected at their lower ends by transverse bars 13, preferably crossed, as shown. The legs 10 and 12 are preferably 50 formed of angle irons, to provide suitable stiffness. At their upper ends, the legs 10 and 12 are pivotally connected by means of pivot elements 14, preferably in the form of bolts. The legs are locked in the open 55 position by means of brace bars 15, pivoted

at 16 to the legs 12, and provided at their free ends with notches 17, engaging over headed studs 18 or the like, secured to the legs 10. It is obvious that the brace bars 15 may be readily disconnected from the 60 legs 10, in which event the two sets of legs may be swung inwardly or collapsed, and will then lie in substantially the same plane.

The barrel receiving portion of the device embodies a ring or hoop 19, and a substantially U-shaped support element or bracket 20. The hoop 19 is provided at diametrically opposite points with openings to pivotally receive the bolts 14, Fig. 5, while the ends of the U-shaped supporting element 20 are 70 also apertured to pivotally receive these bolts. The hoop is split, providing free ends 21, which are spaced, and adapted to be drawn toward each other by a bolt 22. The hoop 19 is adapted to be held at substantially a right angle to the U-shaped supporting element or bracket 20 by means of a diagonal brace 23, pivoted to the element 20, at 24, and provided at its free end with a transverse notch for receiving a headed stud 25, secured to the ring or hoop 19 as shown. When the brace 23 is disconnected from the ring or hoop 19, the element 20 may be 75 swung downwardly with relation to the hoop, and will occupy a position within the legs, as shown in Fig. 4. All elements of the device, when folded, may thus be arranged in substantially the same plane, in a highly compact manner.

Pivoted to the U-shaped supporting element 20, at 26, is a diagonal brace 27, having a plurality of notches 28, adapted to be engaged over a headed stud 29 secured to one leg 10. The function of this brace is to lock the barrel receiving portion of the 95 device in a horizontal, vertical, or angular position.

As shown in Fig. 1, the numeral 30 designates the barrel, which is held within the ring or hoop 19 and the U-shaped supporting element or bracket 20 engages about one end of the barrel. The barrel may be held in a horizontal position, or in a vertical position, and as the barrel is pivoted near its center, it may be easily swung upon the 105 pivots 14.

It is to be understood, that the form of our invention herewith shown and described is to be taken as a preferred embodiment of our invention, and that various changes in 110

the size, form, shape and arrangement of parts may be resorted to without departing from the spirit of our invention or the scope of the subjoined claim.

5 Having thus described our invention, we claim:

A barrel supporting device, comprising oppositely arranged pairs of legs, pivot elements passing through the upper ends of the 10 legs in opposite pairs whereby the pairs of legs may be shifted to opened and closed positions, a brace connected with one leg and adapted for detachable connection with the leg in the opposite pair, a hoop arranged 15 between the upper ends of the legs and apertured for receiving the pivot elements, a substantially U-shaped supporting element hav-

ing its ends apertured and arranged between the upper ends of said legs and pivotally receiving the pivot elements, a diagonal brace serving to detachably connect the hoop and substantially U-shaped supporting elements, and a diagonal brace pivotally connected with the substantially U-shaped 20 supporting element and adapted for detachable engagement with one of said legs, the legs, hoop, and substantially U-shaped supporting element all turning upon the same pivot elements and adapted when collapsed to lie in substantially the same plane.

In testimony whereof we affix our signatures.

BEN F. CULVER.
WILLIAM H. DOYLE.
